INSOLE AND OUTER SOLE COMBINATION

Meyer Margolin, Elgin, Ill.

Application November 30, 1939, Serial No. 306,778

4 Claims. (Cl. 36—3)

My invention relates to a novel insole construction and more particularly my invention relates to a combination of an outsole having perforations therein and an insole provided with resilient lugs adapted to protrude through said outsole.

My invention further relates to a novel shoe construction adapted to provide foot ventilation and foot comfort in the form of a resilient cushion effect in which the cushion effect is obtained by a direct and complete cushioning by resilient material of the foot upon the walking surface.

Another feature of my invention resides in the provision of a pad adapted to be inserted in the inside of a finished shoe for obtaining a snugger fit of the shoe and for enhancing the comfort and breathing properties of the shoe. This pad may be of sufficient size to extend merely from the toe to the arch or this resilient pad may extend from toe to heel. This pad when used in shoe constructions of my invention may contain perforations adapted to match the perforations in the insole or it may contain perforations and coating grooves for obtaining forced breathing. This pad may also carry a metatarsal arch support and a cookie for the long arch of the foot.

Certain of the well known problems in shoe manufacture are flexibility of the shoe and cushioning of the foot as well as the provision of proper shoe ventilation. Because of the necessity of providing an insole in the shoe, which insole is normally relatively stiff material, it has been difficult to obtain the desired flexibility and softness in the shoe.

In my Patent No. 2,153,021 and my co-pending applications Serial No. 257,351, Serial No. 272,364, and Serial No. 290,559, of which the present case is a continuation in part, I have shown various means for effecting increased flexibility, softness and shoe ventilation. According to my present invention, I provide increased resilience broadly by providing that the foot rest on a resilient cushion which is in direct communication in certain areas with the walking surface. Further, the protruding resilient lugs which provide this direct communication are so constructed as to be adapted to be compressed, providing a further cushioning effect.

The compression of the resilient lugs also compresses adjacently positioned grooves thus enhancing the forced breathing effects of such grooves.

Broadly, my new construction comprises an insole which may be resilient throughout its area or may comprise a resilient insert in the fore-

part of the insole, as desired, and in either of these alternative constructions I provide affixed to the forepart of the resilient insole or insert, lugs adapted to extend downwardly from the resilient insole and through openings in the outsole so that such lugs come in direct contact with the walking surface. Because these lugs are positioned in openings that conform closely to the cross-sectional contour of the lug, the compression induced on the lug during the act of walking, seals the opening so that no water or dampness can penetrate therethrough.

I also provide in this construction for grooves located in said resilient forepart of the insole, which grooves are adapted to be flexed in the act of walking and through a communicating channel force and receive air from a perforation which extends through the resilient insole to the inner portion of the shoe.

Accordingly, it is an object of my invention to provide a novel shoe construction with direct cushioning effect while preserving the advantages of insole and outsole construction.

It is a further object of my invention to provide a novel shoe construction in which I provide a preformed resilient insole which carries integrally affixed to the resilient insole lugs adapted to protrude down and through cooperating openings in the outsole so that direct contact with the walking surface is effected.

It is a further object of my invention to provide a novel resilient shoe construction in which a preformed metatarsal arch support is provided in the resilient insert for the insole or in the resilient all-over insole itself.

It is a further object of my invention to provide an outsole having openings through it and an insole having a cut out forepart area and a resilient insert for said cut out insole, said resilient insert carrying resilient lugs adapted to protrude downwardly through said openings in said outsole and perforations in and through said resilient insert, transverse grooves in the bottom of said resilient insert, said grooves being adapted to provide air flow under flexing, said air being forced through said perforations in said resilient insert.

It is still a further object of my invention to provide a complete resilient insole, said insole carrying downwardly protruding lugs, said lugs passing through corresponding openings in an outsole and effecting a direct communication with the walking surface.

It is a further object of my invention to provide a pad adapted to lay over the insole and

give the shoe a snugger fit and more comfortable feel.

It is still a further object of my invention to provide a novel complete insole of resilient material carrying perforations and/or breathing grooves adapted to be inserted into a finished shoe to provide the desired advantages of softness and forced breathing.

Further objects of my invention will be apparent from a consideration of the drawing, a description of which here follows.

Figure 1 is a plan view of the novel shoe construction of my invention showing the protruding resilient lugs in dotted line and the various constructions of my resilient insert.

Figure 2 is a cross-section taken along the line 2-2 of Figure 1.

Referring now more specifically to the drawing, in Figure 1 I show an insole 10 with a central cut out area in which is disposed a resilient insert 11 which may be of expanded rubber of the closed cell or open cell type, said resilient insert 11 being provided with a flap 12 which extends about said insert and is integral therewith. This flap 12 is extended at the rear of the insert at the metatarsal area 13. Located on this extension 13 is a metatarsal support 14 provided with perforations 15. The metatarsal support is integrally molded with the insert as is more particularly shown in Figure 2 and provides a support for the metatarsal arch. The resilient insert 11 is secured to the insole 10 by the spaced lines of stitching 17 and 18. Affixed and preferably integral with said resilient insert 11 are depending resilient lugs 19 which may be of gas expanded rubber as is the remainder of the resilient insert. Extending circumferentially around the base of these resilient lugs 19 are shoulders 23 which bear against the outsole 24 as shown in Figure 2 and thus improve and add to the sealing between the lug and the outsole.

To provide breathing and ventilation for the shoe transverse grooves 20, the walls of which are spaced one from the other are provided on the bottom of the resilient insert and are adapted to force air through perforations 21 carrying reinforcing bosses 22 at their bases.

Referring now to Figure 2 there can be clearly seen that the downwardly extending lugs 19 pass through openings in the outsole 24, which openings are in close conformity with the size and shape of the lugs 19. It will be noted that the extreme lower part 25 of the lug 19 extends beyond the outsole 24 and is in direct contact with the walking surface 26. Thus, under normal foot pressure, the resilient lugs 19 are spread under the walking pressure so that they are in close and compressed contact with the walls of the openings in the outsole 24. This close pressure contact forms a complete seal against the penetration from the outside of any water in the event that the shoes are worn in inclement weather.

The flexing of the grooves 20, which is effected by the flexing of the entire forepart of the insole in the act of walking causes the alternate expression and intake of air through the adjacent perforations 21.

As a further precaution for insuring the sealing of the outsole openings through which the lugs 19 protrude, I may provide rigid inserts 27 and 28 which may be of metal, plastic or any suitable material. These inserts may, for example, be formed during the molding of the rubber insole or insert or may be placed therein in

a stage of its manufacture. It will be noted that the rigid insert 27 is substantially spaced from the outsole and does not interfere in any way with the cushion effect of the rubber insert or insole 11. When pressure of the foot bears down against the walking surface 26 the insert is pressed down under the compression as shown by the position of the rigid insert 28. In this position the edges of the rigid insert, which are flange-like in nature, are forced down over the edges of the opening in the outsole; the flanges of the rigid insert thereupon compress the rubber between the flange of the insert and the outsole at 29 and effectively seal the opening against the entrance of air or moisture. It will be noted however that the rigid insert does not interfere with the resilience and cushioning effect of my novel structure even in this sealing position.

It is an important feature of my invention that the resilient lugs which extend through the outsole and are in direct communication with the walking surface and which absorb the first contact of the foot on the walking surface and are compressed thereby have a second distinct advantage. Pressure on the downwardly depending lugs assists in the compression of the transverse grooves and thereby increases the air flow which it is desired to force through the perforations into the shoe. In the provision for shoe ventilation according to this system of transverse grooves and adjacent perforations as shown in my continuation applications above referred to, the forced breathing is effected principally by the flexing action of the shoe in walking.

It will now be noted that I provide a further auxiliary means for increasing forced breathing action of my novel insert in the form of these lugs which are alternately compressed and decompressed in the action of walking. This compression and decompression of the resilient lugs in turn effects the compression and decompression of the transverse grooves and increases the breathing action derived therefrom.

It is to be understood that I can use as many of the downwardly protruding resilient lugs as is found desirable and these may be few in number as shown in the above specific illustration of my invention or they may be large in number and dispersed throughout the insole. These lugs may be large in diameter or small depending upon their number and upon the degree of softness desired. Further cross-sectional shapes other than circular for such resilient lugs may be employed, as for example cross-sections which are diamond shaped, rectangular shaped, square, etc.

The resilient material referred to above may be rubber of the open cell or closed cell gas expanded types, cork or any material that has desirable resilient properties.

It will be understood that the specific description and drawing have been employed to describe my invention by way of example only and I intend to be limited not by the details hereinbefore shown but only by the claims hereto appended.

I claim:

1. In combination an insole and an outersole, said insole having downwardly extending lugs of resilient material, said insole having perforations extending through said insole, grooves in said insole, the long walls of said grooves being spaced apart from one another, said grooves being adjacent to said downwardly extending lugs, means for affording communication between said

grooves and said perforations, openings in said outersole said openings corresponding in shape to the cross section of said lugs, said lugs extending into and through said openings so as to come in direct contact with the walking surface, said protruding resilient lugs being compressed by pressure contact with the walking surface, whereby said grooves are compressed and air is forced through said perforations to the interior of the shoe.

2. In combination an insole and an outersole, said insole having downwardly extending lugs of resilient material integrally formed therewith, said insole having perforations extending through said insole, transverse grooves in said insole, the long walls of said grooves being spaced apart from one another, said grooves being adjacent to said downwardly extending lugs, means for affording communication between said grooves and said perforations, openings in said outersole, said openings corresponding in shape to the cross section of said lugs, said lugs extending into and through said openings so as to

come in direct contact with the walking surface, said protruding resilient lugs being compressed by pressure contact with the walking surface.

3. In combination an insole and an outersole, 5 said insole having downwardly extending lugs of resilient material, openings in said outersole, said openings corresponding in shape to the cross section of said lugs, said lugs extending into said openings, and rigid inserts disposed in said lugs 10 and positioned at the base of said lugs above said openings.

4. In combination an insole and an outersole, 15 said insole having downwardly extending lugs of resilient material, openings in said outersole, said openings corresponding in shape to the cross section of said lugs, said lugs extending into said openings, and rigid inserts disposed in said lugs 20 and positioned at the base of said lugs above said openings, said rigid inserts having in at least a part of their area a diameter greater than said openings.

MEYER MARGOLIN.
